UNITED STATES PATENT OFFICE.

ALBERT LATHAM, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LAST.

1,282,244.

Specification of Letters Patent.

Patented Oct. 22, 1918.

Application filed March 8, 1916. Serial No. 82,886.

To all whom it may concern:

Be it known that I, ALBERT LATHAM, a citizen of the United States, residing at Beverly, in the county of Essex and State 5 of Massachusetts, have invented certain Improvements in Lasts, of which the following description, in connection with the accompanying drawings, is a specification, like reference characters on the drawings indicating 10 like parts in the several figures.

This invention relates to lasts for use in the manufacture of boots and shoes. It has been found that the provision of sufficient lasts to keep pace with the rapidly changing 15 styles in foot-wear entails the outlay of a great deal of money on the part of shoe manufacturers. Inasmuch as the changes in style are made almost entirely in the fore-parts of the lasts, it has been recognized as 20 desirable to make the heel parts detachable in order that the same heel part may be used with a number of fore parts of different styles.

It has also been found that the pressure of 25 the heelng machine destroys the heel part of a last before the fore part is worn out and it has been found to be advantageous to remove the heel part while the fore part remains in the shoe and heel the shoe directly upon an anvil plate on the heelng machine. It is an object of my invention 30 to provide a last having a heel part easily detachable from the fore part while the last is in the shoe and which shall be strong, 35 light, and cheap to manufacture.

A feature of my invention is a last having a hook and pintle hinge connection, the opening in the hook being vertically directed when the last is in collapsed position, where- 40 by the heel part may be easily lifted away from the fore part when a last is in a shoe.

It has been found that it is advisable to place the hinge in a hinged last as close to the tread face as possible since all that portion 45 of the last above the hinge shortens with the first movement of the hinge. Separable hinged lasts with upturned hooks on the heel parts have been proposed, but, since such a hook must engage under its pintle, it 50 has been found necessary to place the pintle higher than would be otherwise advisable. The illustrated construction embodies also a feature of the invention which avoids this difficulty, namely, a last having a fore part

carrying a pintle and a heel part carrying a 55 downturned hook, whereby the hinge connection may be placed close to the tread surface of the last and rapid shortening and easy removal of the heel part from the shoe is secured.

This and other features of the invention, comprising certain arrangements and combinations of parts, will be explained in the following specification and pointed out in the claims.

In the drawings which show a preferred embodiment of my invention,

Figure 1 is a perspective view of a last, Fig. 2 is a side elevation partly broken away, and

Fig. 3 is an exploded view of the hinge.

The fore part 1 carries a yoke 2 which is doweled into the fore part by one or more dowels 3, and is approximately half the lateral thickness of the last in width. The 75 yoke carries at its outer end a horizontal pin 4. It will be seen from Fig. 3 that the yoke is very substantially constructed. The abutment block 5 is doweled at 6 to the upper portion of the fore part and carries a 80 small dowel 7 to hold it in proper alinement. It has a lock pin 8 on its upper surface. The heel part of the last carries on its forward face a downturned hook 9 which fits between the arms of the yoke 2. At the upper front 85 corner of the heel part is a pivoted locking bar 10, which locking bar has a hole in its front end adapted to engage the pin 8 whereby the fore part and heel part are positively held against relative movement in 90 either direction.

The bar 10 is drawn downward by a spring 11 which is fastened at one end to the heel part and rests in a notch in the lower side of the bar 10. The upper side of the 95 bar 10 has a boss 12 designed to be engaged by a suitable projection upon a jack in order to unlock the last. The abutting faces of the heel part and fore part have tongue and groove engagement at 13 to assist in 100 holding the heel part and fore part in alinement.

The dowels are bored out at 14 for the sake of lightness. The thimble 15 is shouldered at 16 to support the heel plate 17 105 and is reduced at 18 for the sake of lightness. The wooden plugs 19 and 20 are for tacks as is well known and the thimble 15

is bored at 21 in order to secure lightness and to facilitate the removal of a worn out plug 20.

When the locking bar 10 is disengaged from the pin 8 the heel part can be rotated about the pin 4 until the tongue and groove 13 are disengaged and the heel part can be then lifted away from the fore part. It will be clear that it is not necessary to move the heel part backward in order to unhook it from the fore part as would be the case if the hook 9 were turned up instead of down. The open portion of the hook is so directed as to make possible the lifting of the heel part vertically out of the shoe as soon as it has been turned up to meet the fore part. It will be seen also that the turning downward of the hook permits the pintle 4 to be nearer the tread face of the last than would be possible in the case of an upturned hook.

Having described my invention, what I claim as new and desire to secure by Letters Patent of the United States is:—

25 1. In a last, a fore part and a heel part, one carrying a pintle, the other carrying a hook, said hook and pintle constituting a hinge about which said fore part and heel part are constructed and arranged to turn 30 relatively in order to collapse the last, the heel part being constructed and arranged to be removable from the shoe after collapse without disturbing the fore part, and the open portion of said hook being directed

substantially parallel to the direction of removal of the heel part when the heel part is in collapsed position.

2. In a last, a fore part having a pintle, and a heel part having a downturned hook constructed and arranged to engage said pintle and to turn upon it with said heel part, into collapsed position.

3. In a last, a fore part having a pintle, and a heel part having a downturned hook constructed and arranged to engage said pintle and to turn upon it with said heel part into collapsed position, the open portion of said hook being substantially perpendicular to the tread face of the last when said heel part is in collapsed position.

4. In a last, a fore part, a pintle relatively near the tread face of said fore part, and a heel part having a downturned hook constructed and arranged to engage said pintle and permit the collapse of the last, the open portion of said hook being directed substantially perpendicular to and directly toward the tread face of the fore part when the heel part is in collapsed position.

5. In a last, a hinge comprising a yoke having parallel arms spaced apart approximately half the width of the last, and a pintle extending between said arms and a hook member substantially fitting between said arms and over said pintle.

In testimony whereof I have signed my name to this specification.

ALBERT LATHAM.
